US00D913633S

(12) United States Design Patent (10) Patent No.: US D913,633 S
(45) Date of Patent: * Mar. 23, 2021

(54) ITEM OF APPAREL

(71) Applicant: Donna Macan Yadrich, Kansas City, KS (US)

(72) Inventor: Donna Macan Yadrich, Kansas City, KS (US)

(73) Assignee: Donna Macan Yadrich, Kansas City, KS (US)

() Term: 15 Years

(21) Appl. No.: 29/643,573

(22) Filed: Apr. 10, 2018

(51) LOC (13) Cl. 02-02

(52) U.S. Cl.

USPC D2/717

(58) Field of Classification Search

USPC D2/847, 840, 717, 720

CPC A41D 13/1245; A41D 13/1236

(57) CLAIM

The ornamental design for an item of apparel, as shown and described.

DESCRIPTION

FIG. 1 is a front perspective view of the item of apparel showing the new design in a closed configuration.

FIG. 2 is a front view of the item of apparel of FIG. 1.

FIG. 3 is a rear view of the item of apparel of FIG. 1.

FIG. 4 is a right side view of the item of apparel of FIG. 1.

FIG. 5 is a left side view of the item of apparel of FIG. 1.

FIG. 6 is a top view of the item of apparel of FIG. 1.

FIG. 7 is a bottom view of the item of apparel of FIG. 1.

FIG. 8 shows the item of apparel of FIG. 1 in a semi-open configuration.

FIG. 9 shows a close-up perspective view of an attachment mechanism of the item of apparel of FIG. 1; and,

FIG. 10 shows the item of apparel of FIG. 1 in an open configuration.

Broken lines in the drawings illustrate claimed stitching.

1 Claim, 7 Drawing Sheets
